The ornamental design for a holder for a bottle for mounting in a reservoir such as toilet tank, as shown and described.

DESCRIPTION

In a preferred embodiment, the nature of this product is a holder for a bottle suitable to be mounted in a reservoir such as a toilet tank.

FIG. 1 is a top, right, front perspective view of a bottle holder embodying our new design;

FIG. 2 is a front elevational view thereof, the rear view is identical;

FIG. 3 is a right side elevational view thereof, the left side elevational view being a mirror image of the right side shown;

FIG. 4 is a rear elevational view thereof;

FIG. 5 is a top plan view thereof; and,

FIG. 6 is a bottom plan view thereof.

The broken line representations of mounting structure in FIGS. 1-6, of a float assembly in FIGS. 1-4 and 6, and of internal structure in FIGS. 5 and 6, are for the purpose of illustration only, and form no part of the claimed design.
